signors to The General Electric Company
Limited, London, England

Application October 9, 1934, Serial No. 747,540
In Great Britain October 5, 1933

9 Claims. (Cl. 187—29)

This invention relates to lift or like controlling systems, and has for its object the cheapening of such systems whilst at the same time improving in certain points on their reliability.

5 In connection with certain automatic or semi-automatic lift controlling systems, it is necessary that the control mechanism shall possess some indication of the position of the lift at any instant. This indication may be employed to determine, for example, the direction in which a lift is to travel when a calling or starting button is pressed, or to give a visual indication of the lift's position, or for like purposes. In this connection it is known to provide facsimile or reduction gearing operated directly or indirectly from the winding drum of a lift, which gearing drives a multi-contact switch affording the required indications. This method, though fairly certain in action, is costly and requires skilled 20 maintenance.

An alternative known method of affording indication of a lift's position is to cause the said lift to supply current impulses at particular points in its travel to a group of relays the operated ones of which receive current continuously, the said relays operating and remaining energized in sequence as the lift passes the said points. The objections to this method are that a current of greater or less dimensions is continuously employed in maintaining some or all of the relays energized, and that should this current supply fail, then even if the lift does not move, restoration of the current does not re-energize the relays necessary to afford indication of the lift's position.

40 A single step-by-step switch has also been employed to afford an indication of the position of a lift, the said switch receiving "up" or "down" impulses of momentary character only as the lift is in motion, and maintaining itself in the position to which it was last impulsed without the use of a steady current, being impulsed forwards or backwards in accordance with the direction of travel of the lift.

45 According to the present invention, two single-motion step-by-step switches are employed, all "up" impulses being fed to one switch and all "down" impulses to the other. The switch which at any time is not being impulsed to follow the 50 motion of the lift carriage, is later automatically impulsed to take up an equivalent position to that occupied by the other. When this condition is satisfied, both switches remain at rest until one or the other is again impulsed, when the 55 cycle of operations is repeated. Indication of

the lift's position is obtained from a bank of the switch which is being, or was last, impelled.

In order that the invention may be clearly understood, one embodiment thereof will now be described with reference to the accompanying drawing which shows, by way of example, the circuit of a system for controlling an electrically operated lift serving six floors.

Referring to the drawing, it will be seen that the lift L is suspended by a cable LC passing over a drum LD and having a counter-weight CW thereon, the drum being driven by the motor DM. The motor driven shaft is provided with a brake drum with which there cooperates a brake shoe BB normally effective but arranged to be released by a brake magnet BR. At each floor, there is located a gate switch JA to JF connected in series by leads 2G and with a positive source of potential at 3G at one end, the switches being in series and connected by lead 3J with a gate 20 relay J connected to the negative. Thus it will be seen that when all the gate switches are closed, the gate relay J is operated and the contact thereof j_1 will be closed so as to deliver positive potential to the lead 4, for the purpose later 25 described.

At each floor, there is a push button PA to PF provided with contacts arranged to cross connect two main leads 5 and 6, the lead 5 leading back to a connection with a short lead 7 having open contact s_{h2} at one end and closed contact s_{d1} at the other end, the latter contact being normally closed on a short lead 8 connected with closed contact e_2 from which positive potential at 9 is derived. It will be seen that when one of the push buttons PA to PF is closed positive potential from lead 5 will be delivered through lead 6 to closed contact s_{h1} and lead 10 to a self-operating contact c of a wiper switch stepping magnet C, thence through the lead 11 and the magnet to negative. The wiper switch stepping magnet C upon being operated steps the wipers of two wiper switches C1 and C2.

The push buttons PA to PF also have contacts closing when a push button is operated to deliver the positive potential from lead 5 through one of the lamps LA to LF, these lamp circuits being connected to individual leads 12A to 12F, which as will be seen are connected to the wiper contacts of wiper switch C1.

50 It will be noted that from near the lamps LA to LF, "ticks" ta to tf are shown, which simply indicate that there may be corresponding lamp circuits in the lift L and similarly "ticks" th_2 and th_1 , shown at the lower ends of the leads 5 55

and 6, are adapted to connect with corresponding push buttons arranged in the lift car.

It will be seen that the wiper of wiper switch C1 is connected by lead 13 with a call confirming relay SH, which as shown, is connected directly with the negative. Accordingly when call confirming relay SH is operated, its contact sh2 connects a lead 14 with lead 7 and thence through contact sd1 lead 8 and contact e2 to the positive at 9 to thereby provide a holding circuit for the relay SH. Call confirming relay SH also operates contact sh1 to cut the current from lead 6 to lead 10 and stop the stepping of magnet C, and contact sh3 for the purpose hereinafter described.

Two equalizer switches US, with wiper switches US1, US2 and DS, with wiper switches DS1, DS2 are provided, each being adapted to be stepped by the respective stepping magnets US and DS operating self-stepping contacts us and ds as hereinafter explained. It will be seen that the stepping magnet US is connected by lead 15 with the left hand contact at a3 and the stepping contact us, through lead 16 is connected with the right hand contact at a2 and similarly stepping magnet DS is connected through lead 17 with the right hand contact at a3 and its stepping contact ds, through lead 18 with the left hand contact at a2. The contacts at a2 and a3 are adapted to cooperate with contactors A2 and A3, the contactor A2 being connected by lead 19 through contact s1 to positive potential at 20; and contactor A3 is connected through lead 21 with a contact r1 which when closed connects to positive at 22. The contact r1 is adapted to be closed by an impulse relay R, arranged to be operated by inductor plates AB, BC, to EF located between floors in the lift shaft so that as the lift travels from floor to floor, a current impulse will be sent to stepping magnet US or DS, as later described.

The contactors A2 and A3, together with a contactor A1, are mechanically connected with the two-position armature of a direction relay A having two magnet coils, one of which is connected by lead 23 with a contact ur1 which closed connects to positive at 24; and the other coil through lead 25 and contact dr1, closed, to positive at 26. The two position direction relay A is substantially of the type shown in British specification No. 354,847.

It will be noted that the contacts of wiper switches US1 and DS1 are connected together by leads 27a to 27f and the wiper of wiper switch DS1 is connected to the positive at 28, while the wiper of wiper switch US1 is connected by lead 29 with an equalizer relay S, which is operated by being connected to the negative. Also note that a lead 30 connected from positive at contact e3 to lead 29 is arranged to supply current for operating the equalizer relay S under certain conditions.

It will be seen further that the wiper contacts of wiper switches US2, DS2 and C2 are connected in parallel by means of interconnecting leads 30a to 30f and with spaced points on a potentiometer P, the latter being connected at one end with the positive potential at 31 and with the negative at 32. The wipers of wiper switches US2 and DS2, it will be seen, are connected by the respective leads 33 and 34 with the two contacts at a1, which are associated with the contactor A1 connected as indicated later and previously referred to as operated by the direction relay A.

The wiper of wiper switch C2, previously referred to, is connected by lead 35, 35a through contact shs, closed, or e4, closed, and 36, 36a with one coil of a two-coil polarized direction

controlling relay B, the two coils of which are connected in series through lead 37 and the second coil being connected by lead 38 with the contactor A1, previously described as operated by direction relay A. It will be seen that the armature contact arm 39 of the polarized relay B which is normally central is connected with the positive potential at 40 and the arm cooperates with two contacts at b1. One of contacts b1 is connected by lead 41 with up-call relay UR, the circuit of which is continued through lead 42, contact dr3 and lead 43 to brake relay E, which is connected to the negative. The other contact at b1 is connected by lead 44 with the down-call relay DR, which is connected through lead 45, contact ur3 and the same lead 43 with brake relay E.

An inductor floor relay Q located in the lift car is arranged to be operated by inductor plates QA to QF located in the shaft at each floor. Floor relay Q is arranged when operated to open contact q1 which supplies positive from 46 through lead 47 to contact sd2, shown open, but which when closed on an associated contact is arranged to deliver current through lead 48 to operate brake magnet BR, which is connected with the negative. It will be noted that the brake magnet BR may also be operated through lead 49 from contact e1 when closed on the positive from 50, the latter being normally connected by the associated contact at e1 through lead 51 with brake magnet operated contact br1, which by connection through lead 52 with the upper coil of the isolating relay SD carries positive potential to operate the latter, which is connected to negative. The isolating relay SD is provided with another coil which is connected by lead 53 and through a self-operated contact sd3 with a timing circuit TD leading to a timing device BM through the heating coil HC, supplying positive potential from D53.

The up-call relay NR, in addition to operating contacts ur1 and ur3, operates contacts ur2 to close the positive circuit from lead 4 and contact j1 on lead 54 connected to up drive contactor U, which is provided with a holding circuit contact u1 connected by lead 55 with the positive at brake magnet operated contact br3; and similarly, down-call relay DR, besides operating contacts dr1 and dr2, operates dr2 which connects the positive from contact j1 and lead 4, by lead 55 with down drive contactor D having a holding circuit contact d1 connected by lead 57 through brake magnet operated contact br2 with positive potential.

The two single-motion follower equalizer switches US and DS, preferably of the type disclosed, for example, in British specification No. 349,180, rotating always in the directions of the arrows, are arranged to follow the motion of the lift carriage L in the shaft, the up equalizer switch US following the upward motion and the down equalizer switch DS following the downward motion of the carriage. The call registering switch C which is provided for storing calls made for the lift carriage also, rotates only in the direction of the arrow on the drawing.

A group of call buttons and associated indicator lamps mounted in the lift carriage is connected to the floor button circuit through leads indicated by the dotted line. The function of each of the buttons and lamps of this group is identical with that of the individual floor buttons and lamps and these are not shown in detail in the drawing.

The system is adapted so that the lift carriage travels to the floor corresponding to the call-button depressed. Thus, if the carriage is at the first floor and a user on the fourth floor wishes 5 to travel to the second floor, he first depresses the call-button PD mounted at that floor. The carriage then travels to the fourth floor and the user enters; finally by depressing the second floor call-button in the carriage, the user is taken to 10 the second floor.

The two-position direction relay A takes up one of its two positions according as the lift carriage is required to travel upwards or downwards. In the drawing, the relay is shown in 15 the position required for upward travel of the carriage.

The three-position direction controlling relay B which, as previously indicated, is provided for controlling the direction of motion of the carriage is normally in the central position shown, but if the carriage is required to travel upwards 20 it is operated to the right, in the drawing, and if the carriage is required to travel downwards it is operated to the left. The position of the contactor 39 of the direction controlling relay B is 25 dependent on the position of the equalizer switches US and DS since it is connected with wipers US2 and DS2 of the latter through leads 33 and 34 and its operation will be more fully understood from the description of the operation 30 of the system in answering a typical call.

It will be understood that the system is rendered inoperative by release of the gate relay J, the latter being released when one of the gate-operated switches JA—JF is opened at one of 35 the floors. The gate relay J is always operated when all the gate-operated switches are closed, thereby indicating that all the gates are shut and permitting the system to be started.

40 The inductor-type floor relay Q is mounted, together with an intermediate inductor-type impulse relay R, on the lift carriage and these relays are adapted to be operated by indicator plates QA—QB and AB—EF, which are mounted 45 in the lift shaft.

The floor-operated relay Q is always in operated position whenever the lift carriage is stationary at any of the floors.

The intermediate impulse relay R is operated 50 whenever the lift carriage moves between two consecutive floors, the indicator plates AB—EF therefor being arranged midway between the floors, these plates being different from those arranged at each of the floors for operating relay Q.

55 It will be noted that the call confirming relay SH by operating contactor sh1 is arranged to arrest the stepping of call-registering relay C when it steps to the contact corresponding to the floor to which the lift carriage is to travel and when this occurs, the lamp of the group LA—LF corresponding to that floor is operated through its line 12A—12F to confirm to the user that his call has been registered.

60 In the position of the lift carriage shown in the drawing, the lift being at its lower limit of travel, i. e. at floor 1, the gate relay J (all gates closed), the equalizer relay S. (DS1—US1 and line 29) and the floor relay Q (inductor plate 65 QA) are all operated; the contacts of these three relays are shown, however, on the drawing in an unoperated position to agree with current practice.

65 Assume now that the fourth floor call-button 75 PD is depressed, either in the lift car or at floor

4, indicating that the lift is required to travel to floor 4. Depression of this button completes a circuit from positive at e2, via lead 8 contact sd1, lead 5, the said call-button PD contacts, lead 6 back to contact sh1 and then through lead 10 contact c, and lead 11 to the stepping magnet C of the call-registering switch C1. This switch then steps by self-interruption at its contact c in a manner known in the telephone art until the wiper of switch C1 reaches the contact in the bank 10 (fourth) which is connected by lead 12D, with the contact of call-button PD, through lamp LD, thereby operating the call-confirming relay SH by current via negative through relay SH and lead 13 to the said bank contact 15 (fourth) and by lead 12D to the indicator lamp LD in series with contacts of call-button PD and thence through leads 5, 7, contact sd1, and lead 8 to positive at the closed contactor e2, and indicator lamp LD lights, indicating to the caller 20 that the call has been registered and that the button can be released. Upon operation of call-confirming relay SH the contacts operated thereby operate as follows:—

sh1 interrupts the stepping of call registering 25 switch C.

sh2 locks relay SH operated to positive via lead 14 contact sh2, leads 7 and 8 and contacts sd1 and e2 so that if the call-button PD is released before the brake relay E operates, as described later, call registering switch C is not stepped further by contact sh1.

sh3 closes the circuit from the wiper of switch C2 between leads 35 and 36 to direction 35 controlling relay B.

It will be noted that when the stepping magnet C moves its wiper C2 out of agreement with the wipers of equalizer switches US2 and DS2, certain sections of the potentiometer P are short-circuited and the direction controlling relay B 40 operates when contact sh3 closes. In the example given the current then passes from the plus at 31 of the potentiometer P through lead 30a to the first contact of US2, then through lead 33 to the left contact a1, then by contactor A1 and 45 lead 38 to the direction controlling relay B and through leads 37, 36, contact sh3, lead 35 to the wiper and fourth contact of C2, lead 30d to the potentiometer P and negative at 32. The contact arm 39 is then operated in a direction (to 50 the right contact b1 in the drawing) to operate up call relay UR and brake relay E, the circuit being completed from the plus at 40 through the contact arm 39 of direction controlling relay B through lead 41 from contact b1 through UR, lead 42, contact dr3, lead 43 and to minus beyond brake 55 relay E.

With the operation of up-call relay UR and brake relay E, the following contacts are operated by these relays:

e1 by closing opens the contact on lead 51 and 60 operates the brake magnet BR from the positive at 50 via lead 49, contact sd2, (contact sd2 being open), and lead 48, thereby removing the brake BB from its drum. It will be noted that closing e1 at the same time opens a circuit from the positive 50 through lead 51, contact b1 and lead 52 to isolating relay SD which, through opening of its contact sd1, isolates the call button circuits through leads 7 and 5 from the positive 65 at 9. It will be noted that contacts b1, b2 and b3 are operated by the brake magnet BR.

e2 opening deenergizes call confirming relay SH thereby closing contact sh1, but e2 opens the push button circuit leads 8, 7, 5 etc. and prevents fur- 75

ther calls from being made until the lift reaches its destination, the operating positive potential at 9 being removed from the buttons PA—PF.

e_3 closed on lead 30, connected to lead 29, holds 5 equalizer relay S operated to the positive while equalizer wiper switches US1 and DS1 are stepping.

e_4 by closing leads 35a and 36a maintains the 10 circuit through the wiper of switch C2 to direction controlling relay B when contact sh_3 is opened by deenergization of call confirming relay SH, by the opening of e_2 as previously explained.

ur_1 closed energizes one coil (left as shown) of 15 direction relay A from positive 24 through lead 29 but does not move the armature as the relay A already has its armature in the direction in which it is now attracted.

ur_2 closed on lead 4 and through lead 54 energizes the up drive contactor U from positive on 20 closed contact j_1 causing the lift to move upwards under the influence of the driving motor DM.

ur_3 opens between leads 43 and 45 and, being 25 an interlocking contact, by opening prevents accidental operation of down call relay DR through lead 44 from contact b_1 . Upon energizing the up drive contactor U, its contact u_1 locks this this contactor operated to contact br_3 , now closed as previously explained.

30 The lift now traverses the shaft towards the required floor (fourth) releasing floor relay Q and closing its contact q_1 on lead 47, but since contact sd_2 is open there is no current from positive at 46, the brake magnet BR being energized 35 from e_1 by the positive at 50 through lead 48. Midway between each floor the lift passes an indicator plate AB, BC, CD, in the shaft which momentarily operates the impulse relay R. Upon 40 operation of the impulse relay R its contact r_1 is closed. Contact r_1 by closing operates the switch magnet US once for every plate passed, the current passing from the positive 22 at r_1 , via lead 21, contactor A3, left contact a_2 (the direction relay A standing as shown) lead 15 through the 45 relay to negative so that when the indicator plate CD between floors 3 and 4 is passed, the wipers of the call registering switch C and up equalizer switch US, US1, US2, will occupy like positions (fourth contact, corresponding to call button PD) 50 on their respective banks, with the result that the wipers of wiper switch C2 and wiper switch US2 will be connected through lead 20d to the same point on potentiometer P and the direction controlling relay B is short-circuited, thereby 55 permitting its armature to return to the central position; thus opening the circuit at b_1 on lead 41 and releasing up call relay UR and brake relay E. Note that in stepping the wiper of equalizer switch US1 forward into register with the 60 wiper of call register switch C1 it steps out of register with the wiper of equalizer switch DS1 and in so doing removes the latter's energizing current from positive 28 through leads 21a and 29 from equalizer relay S, but the latter is held 65 through lead 30 from positive at contact e_3 .

While direction controlling relay B is deenergized, up call relay UR and brake relay E are de-energized with the following results:

e_1 by opening connects the positive at 50 to 70 lead 51 and permits the current to operate isolating relay SD via contact br_1 , the latter still being closed by the brake magnet BR. In the same opening movement of contact e_1 the latter opens its circuit through leads 49, 48 to the brake magnet BR but isolating relay SD being oper-

ated at the same time its contact sd_2 closes on lead 48 and holds the brake magnet BR operated from positive 46 on contact q_1 through lead 47.

e_2 closes to positive at 9 but since contact sd_1 is opened at the same time, with operation of 5 isolation relay SD, so that push button calls can have no effect.

e_3 now opens the positive to lead 30 and releases equalizer relay S with the result described below.

e_4 opens, but since the circuit 35, 35a, 36a, 36 10 through direction controlling relay B has been neutralized (wipers C2 and US2 in register) nothing happens.

sd_3 locks the isolating relay SD operated to a positive potential D53 derived from the circuit 15 TD of a time relay, comprising a heating coil HC and a bimetallic strip BM and operating in known manner, and this circuit supplies the said potential for a predetermined period after closure of contact sd_3 . 20

Equalizer relay S being deenergized as described, contact s_1 closes on the positive at 20 and completes a circuit through lead 19, contactor A2, left contact a_2 , lead 18, contact ds and to negative through DS which causes equalizer 25 switch magnet DS to step the wiper of wiper switch DS1 by self-interruption at contact ds in the direction shown by the arrow until the wiper of switches US1 and DS1 are in register and occupy like positions on their banks, that is, fourth contact and positive at 23 can then pass from wiper of DS1 through lead 27d to wiper of US1 and lead 29, which reoperates equalizer relay S and its contact s_1 by opening stops the stepping of equalizer switch DS. 30

The lift now runs to the floor level required. When nearly or substantially at the required position at the fourth floor, in example given, inductor floor relay Q is operated by the levelling inductor plate QD in the lift shaft, and by the 40 opening of its contact q_1 deenergizes the brake magnet BR through leads 47 and 48 and contact sd_2 , (e_1 being already open) allowing the brake BB to close and stop the lift. Upon deenergizing brake magnet BR, its contacts br_1 , br_2 and br_3 45 open, the opening of contact br_3 cuts the circuit through lead 55, contact u_1 , of the up drive contactor U to stop the motor. After a short interval determined by the timing circuit TD, to allow the gate to be opened, isolating relay SD 50 is released from the positive at D53 by the delay circuits HC and BM, and contacts sd_1 , sd_2 and sd_3 are released. Releasing contact sd_1 closes leads 7 and 5 on lead 3 and the positive 9 at e_2 , and the latter closed, allows further calls to be 55 stored by operation of one of the buttons PA—PF. In normal idle position as previously indicated, equalizer relay S, gate relay J and floor relay Q remain operated.

Assuming now, as a further example, that the 60 lift is at the fourth floor, as just described and the top floor call button PF is depressed, the call registering switch C will be again operated in the manner previously described to step the wiper of wiper switch C1 from the fourth position to 65 the last contact position, where again the circuit from positive 9 at e_2 , through lead 5, button contacts PF, lead 12F, wiper and lead 13 to the isolating relay SH will be completed, and since the wiper of stepping switch C2 is now connected 70 by lead 38f with the potentiometer P at the point nearest its negative end, the current will flow from the positive at 3f through lead 38d and the fourth contact of wiper switch US2 through lead 33, left contact a_1 , contactor A1, lead 38 and the 75

direction controlling relay B, leads 36, contact sh_3 , lead 35 wiper of C2 on last contact and lead 30f to negative 32 in the same manner and in the same direction as before and the up call 5 relay UR will be operated. It will thus be seen that the operation previously described will be repeated and the lift will go to the top floor.

Again assuming that the lift is at the fourth floor, as in the first example, and it is desired to 10 go down to the second floor, the call button PB now is depressed and held down and again call registering switch C is operated, this time stopping the wiper of switch C1 from the fourth contact to the second contact (in the direction of 15 the arrow), thereby completing the indicator lamp circuit through the call confirming relay SH, in the manner previously described, and stopping the call registering switch C with its wiper C1 on the second contact. The lift being 20 at the fourth floor, it will be recalled that the wiper switches US2 and DS2 are in register and both standing on the fourth contact while now the wiper of wiper switch C2 has advanced to the second contact. In this position, the positive 25 current from the potentiometer P now passes in the opposite direction, that is, through lead 30b and the second contact of C2 and through lead 35, contact sh_3 , lead 36, the direction controlling relay B, through lead 38, contactor A1 and left 30 contact a_1 and the lead 33 to wiper switch US2, then through the fourth contact of this wiper switch back through lead 30d to the negative end 32 of the potentiometer P, thereby operating 35 the direction controlling relay B armature contactor 39 in the opposite direction to close the plus circuit from 40 through left contact b_1 , lead 44 to down call relay DR, lead 45, contact ur_3 , lead 43 and brake relay E. From here on the 40 operation will be substantially as previously described except that now contacts dr_1 , dr_2 and dr_3 are operated. Closing contact dr_1 operates the right hand magnet of the direction relay A to change the position of the contactors A1, A2 and A3 on contacts a_1 , a_2 and a_3 , so that the down 45 equalizer switch magnet DS is operated by operation of impulse relay R as the lift carriage passes the indicator plates CD, BC in the lift shaft and afterward the up equalizer switch US is automatically stepped in the manner previously 50 described to bring the wiper of switch US1 into register with the wiper of switch DS1.

It will thus be seen that in the operation of the down call relay DR the contacts dr_1 , dr_2 and dr_3 operate to perform functions corresponding 55 to those previously described for contacts ur_1 , ur_2 and ur_3 , but now for the downward operation of the lift, the down drive contactor D being now operated instead of the up drive contactor U and held by contact d_1 , through lead 57 and brake 60 magnet operated contact br_2 . The operation of the other relays and contacts of brake relay E and isolating relay SD will be substantially the same as described previously.

Although we have described certain embodiments of our invention we wish it to be understood that these embodiments do not by any means exhaust the possibilities, and that subject to the scope of the appended claims we wish to claim all such embodiments or variations 70 thereof as would be obvious to those skilled in the art.

We claim:—

1. In a lift for serving a plurality of floors, a push button and indicating lamp with cooperating circuits, for each floor, a stepping call reg-

istering wiper switch having contacts corresponding to the floors served, a stepping magnet automatically operated for stepping said wiper switch, the circuit of said magnet being completed by operation of a floor push button, circuit connections from the contacts of said wiper switch arranged to form part of the respective lamp circuits, said circuits being completed by the operated floor push button and a relay in said wiper switch lamp circuit arranged to be 10 operated simultaneously with lighting of the lamp when the stepping wiper switch reaches the contact corresponding to the floor of the operated push button, said relay operating to stop the stepping of said wiper switch. 15

2. In a lift for serving a plurality of floors, as in claim 1, a second wiper switch operated synchronously with the first and by the same stepping magnet, a direction controlling relay, the contacts of said second wiper switch being connected with a potentiometer for controlling current to said direction controlling relay, and call relays arranged to be operated by said direction controlling relay for controlling the up and down movement of the lift. 20

3. In a lift for serving a plurality of floors, as in claim 1, a pair of stepping equalizer wiper switches, each having wiper contacts corresponding to the floors served, leads connecting corresponding wiper contacts together, stepping magnets for the respective equalizer switches, means including a direction relay for determining operation of the equalizer switches according to whether up or down movement of the lift is required, impulse operated contact means and 30 circuits for operating the stepping magnets of the respective equalizer wiper switches for up or down movement arranged to be operated as the lift passes from floor to floor, means arranged to become effective when one of said equalizer 35 switches comes into register with the push button operated switch for stopping the lift at the floor corresponding to the button operated and means for automatically stepping the other equalizer switch into register with said impulse operated 40 equalizer switch. 45

4. In a lift for serving a plurality of floors, a push button for each floor, a stepping wiper switch having contacts corresponding to the floors served, a self stepping magnet for stepping 50 said wiper switch, a circuit common to all floor push buttons for operating said stepping magnet when one of the push buttons is depressed, a relay, the circuit of which is arranged to be completed by said wiper switch when its wiper reaches the contact corresponding to the push button depressed, the operation of said relay interrupting said push button stepping circuit, an auxiliary wiper switch stepping in unison with the first wiper switch and means controlled by 55 said auxiliary wiper switch for determining the direction of movement of the lift. 60

5. A lift for serving a plurality of floors as in claim 4, wherein the means controlled by said auxiliary wiper switch comprises a direction controlling relay, the operating circuit of which is controlled by the position of the lift carriage in cooperation with the auxiliary wiper switch, for determining the direction of travel of the lift carriage according to the push button depressed. 65

6. A lift for serving a plurality of floors as in claim 4, wherein a direction relay controls circuits cooperating with said auxiliary wiper switch which are arranged to control the opera- 70 75

tion of a direction determining relay according to the position of the lift carriage and the floor button operated when registering a call for the lift carriage.

- 5 7. In a lift for serving a plurality of floors, a push button for each floor, a stepping wiper switch having contacts corresponding to the floors, a self stepping magnet for stepping said wiper switch, a circuit common to all the push buttons for operating said stepping magnet when one of the push buttons is depressed, a relay, circuits arranged to be completed by said wiper switch for operating said relay to interrupt said push button stepping circuit when the wiper switch reaches the contact corresponding to the push button depressed, an auxiliary wiper switch stepping in unison with the first wiper switch, a direction controlling relay controlling up and down movement of the lift and circuits controlled by said auxiliary wiper switch for operating said direction controlling relay.
- 10 8. In a lift for serving a plurality of floors, up and down equalizer wiper switches and a call registering wiper switch having contacts corresponding in number with the floors to be served, circuits interconnecting the corresponding contacts of all of said wiper switches with spaced tappings of a potentiometer provided at opposite ends with plus and minus potential, a stepping magnet for said call registering wiper switch having a circuit arranged to be closed by a floor push button for self stepping said call registering wiper switch, means for stopping stepping advance of said call registering wiper switch when it reaches a point corresponding to the floor button operated, a relay arranged to be operated by potential from said potentiometer for controlling the direction of travel of the lift, stepping magnets for stepping the respective equalizer wiper switches, impulse means operated by the lift in passing from floor to floor for stepping

one of said equalizer wiper switches into register with the call registering wiper switch, the equalizer switch so operated depending on the direction the lift is required to travel as determined by the call registering wiper switch in cooperation with said direction controlling relay.

- 15 9. In a lift for serving a plurality of floors, a potentiometer having a corresponding plurality of tappings, a call stepping wiper switch, the contacts of which are connected to said tappings, push buttons for the respective floors, a circuit including a stepping magnet for stepping said call wiper switch when a floor button is depressed, means for stopping the stepping of said call operated switch on a contact corresponding to the floor button depressed, a three-position relay arranged to be operated by current from the potentiometer accordingly as said call wiper switch is positioned for determining up or down movement of the lift, a two-way relay arranged to be operated in one direction when up movement is determined and the other direction with down movement, a pair of stepping equalizer wiper switches, the stepping of which is controlled by the position of said two-way relay, the contacts of said equalizer switches being connected the same as the call wiper switch to corresponding tappings of said potentiometer, means operated by the lift in passing from floor to floor for stepping one of said equalizer switches until its wiper engages a contact corresponding to the floor selected by the push button depressed, said three position relay being deenergized to stop movement of the lift when the wipers of the call and equalizer switches are on corresponding contacts, and means for automatically stepping the other equalizer switch into register with the lift operated equalizer switch.
